CASE FOR A WRIST COMMUNICATION TRANSMITTER

Jack C. Roberts, Malibu, Calif., assignor to Saxton Electronics Corporation, Congers, N.Y., a corporation of New York

Filed Feb. 7, 1968, Ser. No. 10,483

Term of patent 14 years

(Cl. D26—14)

FIGURE 1 is a top plan view of a wrist communication transmitter showing my new design;

FIGURE 2 is a bottom plan view of the case shown in FIGURE 1;

FIGURE 3 is a side elevation with the antenna broken away for convenience of illustration;

FIGURE 4 is an elevation as seen from the opposite side of FIGURE 3; the antenna has been omitted for ease of illustration;

FIGURE 5 is an end elevational view thereof;

FIGURE 6 is an end elevational view taken from the other end thereof;

FIGURE 7 is a fragmentary bottom view, in perspective, of the case of FIGURE 2;

FIGURE 8 is a perspective view of the case; and

FIGURE 9 is a view similar to FIGURE 1 without the antenna.

The broken line showing of a wrist strap and dial ornament in FIGURES 1, 1a, 3, 4, 5, 6 and 8 is merely for illustrative purposes.

I claim:

The ornamental design for a case for a wrist communication transmitter, substantially as shown and described.
